(57) **CLAIM**

The ornamental design for a tape take-up roller, as shown and described.

DESCRIPTION

FIG. 1 is a front perspective view of the tape take-up roller showing the new design;

FIG. 2 is a right side view of FIG. 1;

FIG. 3 is a left side view of FIG. 1;

FIG. 4 is a front view of FIG. 1;

FIG. 5 is a rear view of FIG. 1;

FIG. 6 is a top view of FIG. 1; and,

FIG. 7 is a bottom view of FIG. 1.

Applicant makes no claim to the structure shown in broken lines in the drawings. Furthermore, Applicant notes that the markings on the drawings are for shading purposes only, and are not to be considered a part of the design of the present invention.

1 Claim, 5 Drawing Sheets
